UNITED STATES PATENT OFFICE.

SAMUEL J. MILLER, OF CAMBRIDGE CITY, INDIANA.

FENCE.

SPECIFICATION forming part of Letters Patent No. 329,197, dated October 27, 1885.

Application filed May 21, 1885. Serial No. 166,311. (No model.)

To all whom it may concern:

Be it known that I, SAMUEL J. MILLER, a citizen of the United States, residing at Cambridge City, in the county of Wayne and State 5 of Indiana, have invented certain new and useful Improvements in Fences; and I do hereby declare the following to be a full, clear, and exact description of the invention, such as will enable others skilled in the art to which 10 it appertains to make and use the same:

My invention relates to certain improvements in the construction of fences; and the purpose thereof is to provide a simple, efficient, and comparatively inexpensive all-metal fence 15 having means whereby the terminal or main posts may be retained in a vertical position, the wires kept tense, and the expansion and contraction thereof compensated and permitted.

20 The invention consists in the several novel features of construction and combinations of parts hereinafter fully set forth, and definitely pointed out in the claims annexed to this specification.

25 Referring to the drawings forming part of this application, Figure 1 is a side elevation showing a portion of a fence embodying my invention. Fig. 2 is a plan view of the parts illustrated in Fig. 1. Fig. 3 is a detail view 30 illustrating the construction of the intermediate posts planted between the terminals or main posts.

In the said drawings, the reference-letter A designates the ground-line. The fence is composed of posts *a*, constructed of metal plate 35 rolled or otherwise brought into semicircular form in cross-section and driven into the soil, these posts constituting the terminal or main posts, which are usually placed at the extremities of a line of fencing or at the corners. 40 To these posts are attached, in any suitable manner, the strands *i i*, which are supported at suitable points between the main posts by sub-posts *b*.

45 The sub posts are composed of two parts, one being a semicircular or semi-cylindrical plate, *b'*, which is driven into the soil, and is provided with notches to receive the strands. The other part consists of a brace, *c*, shorter 50 and of less width than the part *b'*, and having semi-cylindrical form in cross-section. The

parts are placed together, the convex faces being turned outward, and the upper end of the brace being placed in and against the concave face of the intermediate post. They are fastened by a bolt, *e*, the point of attachment being such that when the post is driven into the ground the lower end of the brace will rest thereon at a little distance from the post. Connected with each terminal or main post 60 is a sill or ground-plate, *l*, composed of a rigid metallic strip or bar, one end thereof being curved to embrace the post *a*, and having its extremity bent around the edge thereof and lapped down upon its inner face, by which 65 displacement of the sill and turning of the post is prevented. The other end extends some distance from the post, and is bent upward at a right angle, or thereabout, as shown in Fig. 1 at *l'*.

70 The letter *a'* designates a brace, one end of which embraces the post at a point within its upper third, being curved around the same in the manner shown at *d' d''* in Fig. 2, and already substantially described in connection with the 75 manner of constructing the ground-sill. The portion of the brace which is carried around the post is horizontal, but the body part is inclined downward toward the end of the ground-sill, and its end, which is bent into substantial 80 parallelism therewith, lies upon said sill and may abut against the upturned end *l'*. Through this portion of the brace is tapped a screw-bolt, *h*, passing through an opening in the sill 85 *l* and resting upon a plate, *g*, beneath it.

It will readily be seen that by turning the bolt *h* a thrust may be given to the post by which it may be straightened in case it has yielded to the drag of the wires, while at the same time a suitable tension may be imparted 90 to the latter. In cases also where iron strands are employed which are capable of expansion and contraction by changes of temperature this device may be conveniently employed to slacken the wires in winter and restore their 95 tension when warm weather returns.

Having thus described my invention, what I claim is—

1. In an all-metal fence, the combination, with a semi-cylindrical post, of a sill or ground- 100 plate having one end embracing the foot of said post, and a brace similarly attached to its

upper portion and having its end resting upon the sill and abutting against its upturned extremity, substantially as specified.

2. In an all-metal fence, the combination, 5 with a semi-cylindrical post, of a ground sill or plate having one end embracing the foot of the post, a brace similarly attached to its upper portion and inclined downward toward the end of the sill, a screw-bolt tapped through 10 the end of said brace, and a plate beneath the sill upon which the end of the bolt rests, substantially as specified.

3. In an all-metal fence, the combination, 15 with a semi-cylindrical post, of a ground sill or plate having one end curved around the foot of said post, and lapping over its edge upon the concave face thereof, a brace similarly connected to its upper portion and having its end lying upon the sill and abutting against 20 the upturned extremity thereof, a plate be-

neath the sill, a bolt tapped through the end of the brace, passing through the sill, and resting upon said plate, and wire strands supported by said posts and by suitable sub-posts, substantially as specified.

4. In an all-metal fence, the combination, 25 with a post having a ground sill or plate connected to its lower part, of a brace having one end attached to its upper portion and its other end resting upon the ground-sill at a distance 30 from the post, and a screw-bolt tapped through the end of said brace and having its end resting upon a solid support beneath the same, substantially as specified.

In testimony whereof I affix my signature in 35 presence of two witnesses.

SAMUEL J. MILLER.
